UNITED STATES PATENT OFFICE.

ORVILLE C. JOHNSON, OF AURORA, ILLINOIS.

DOOR-OPERATING MECHANISM.

1,234,341.

Specification of Letters Patent. Patented July 24, 1917.

Application filed March 17, 1916. Serial No. 84,932.

To all whom it may concern:

Be it known that I, ORVILLE C. JOHNSON, a citizen of the United States, residing at Aurora, in the county of Kane and State 5 of Illinois, have invented certain new and useful Improvements in Door-Operating Mechanisms; and I do declare the following to be a full, clear, and exact description of the invention, such as will enable others 10 skilled in the art to which it appertains to make and use the same.

My invention which is an operating mechanism for doors has for its object to provide simply constructed and inexpensive 15 means of this class which may be used to advantage for opening and closing the doors of garages and locking them, the mechanism being operated by the weight of an automobile passing thereover.

With this general object in view, the invention resides in certain novel features of construction and in unique combinations of parts to be hereinafter fully described and claimed, the descriptive matter being supplemented by the accompanying drawings 25 which constitute a part of this application and in which:

Figures 1, 2 and 3 are vertical sections showing the application of the invention and 30 illustrating its numerous positions while opening and then closing a door;

Fig. 4 is a horizontal section taken on the plane indicated by the line 4—4 of Fig. 1;

Fig. 5 is an enlarged horizontal sectional 35 view through one side of the door frame and parts immediately adjacent thereto;

Figs. 6, 7 and 8 are detail vertical sections taken on the planes indicated by the lines 6—6, 7—7 and 8—8 of Fig. 5.

In specifically describing the construction shown in the drawings above briefly described, similar characters will be placed on corresponding parts throughout the several views and reference will be herein made to 45 the numerous elements by their respective indices. To this end, the numeral 1 represents a garage in which an automobile is to be temporarily stored, said garage having a doorway 2 whose frame 3 is shown as provided with vertical channel iron guides 4 in which rollers or the like 5 travel, said rollers being carried on the upright edges of a flexible door 6 of any preferred construction, this door being normally closed 55 but being adapted to be wound on a drum 7

to allow the passage of an automobile into or out of the garage.

A sprocket chain 8 passes around a pinion 9 on the shaft of the drum 7 and around a sprocket 10 on a horizontal shaft 11 adjacent the lower end of the frame 3, all of these parts being positioned on the interior of the garage as shown. The shaft 11 is equipped with a driving gear 12 which is operated by the construction to be herein-after described, such construction constituting the most important features of the present invention. Although the specific connections shown and described between the gear 12 and the drum 7 are preferably used, other suitable means might well be provided for transmitting rotary motion between these parts as occasion may demand.

Positioned longitudinally on the automobile path leading to and from the frame 3, are two pairs of door operating tracks or levers 13. Each of these pairs comprises a lever 14 disposed on the exterior of the garage or the like and a lever 15 positioned on the interior of the housing, the levers 14 and 15 being disposed end to end as shown and being pivotally connected preferably by securing longitudinally extending fingers 16 to the levers 15 and by passing said fingers loosely through eyes 17 carried by the levers 14 (see more particularly Fig. 6). The levers of each pair are fulcrumed between their ends as shown at 18, the location of the fulcrums being such as to normally cause the remote ends of said levers to lower as shown in Fig. 1, while the adjacent ends thereof will be spaced vertically from the floor of the building, a pit 19 being preferably provided for the purpose of allowing said last named ends of the levers to move downwardly to rotate the gear 12 through the instrumentality of a rack bar 20 which meshes with said gear, said bar being secured by means of an appropriate bracket 21 to any one of the levers above described.

By constructing the mechanism in the manner described, it will normally stand as shown in Fig. 1, in which position the door will be locked so that only an automobile A traveling onto the outermost levers 14 may open said door. As the automobile moves toward the door, its weight will depress the inner ends of said levers 14 as shown in Fig. 2, thus causing the rack bar 20 to rotate the gear 12 which with the operating

connections above described or the equivalents thereof, will so drive the drum 7 as to raise the door 6. The automobile A now passes into the building and travels along the innermost levers 15, thus moving said levers from the position depicted in Fig. 2 to their normal position with the machine supported thereon. This return of parts to their original positions again closes the door 10 as shown in Fig. 3 and locks the same. In removing the automobile from the garage 1, a reversal of the operation described will take place, and again leaves the door locked.

From the foregoing description, taken in connection with the accompanying drawings, the construction and manner of operation of the invention will be readily understood and it will be obvious that it may be applied to equal advantage upon vertically and horizontally moving doors. The latter may be flexible or rigid as occasion may demand and obviously, numerous other types of connections between them and the operating levers may be used within the scope of the invention as claimed. Also although a number of specific details have been shown and described, numerous changes may be made

without departing from the spirit of the invention.

I claim:

In a door operating mechanism, the combination of a pair of parallel levers fulcrumed centrally and normally disposed horizontally in a garage to support an automobile on their inner ends throughout the length of time it stands in said garage, another pair of centrally fulcrumed levers inclining upwardly to the outer ends of the aforesaid levers and pivotally connected therewith, a door at the meeting ends of said pairs of levers, and operating connections between said levers and door for opening the latter when the meeting ends of the levers are depressed, said levers when held in their normal positions by the weight of the automobile on the inner pair of levers serving to hold the door in closed position.

In testimony whereof I have hereunto set my hand in presence of two subscribing witnesses.

ORVILLE C. JOHNSON.
